(57) **CLAIM**

The ornamental design for a set of nested shaver combs, as shown and described.

DESCRIPTION

FIG. 1 is a front perspective view of a set of nested shaver combs showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a bottom view thereof; and,

FIG. 8 is a top view thereof.

The evenly spaced broken lines illustrate portions of the set of nested shaver combs and form no part of the claimed design. The dash-dot-dash broken lines illustrate the boundary of the set of nested shaver combs and form no part of the claimed design.
